(57) **CLAIM**

The ornamental design for an information handling device with graphical user interface, as shown and described.

DESCRIPTION

FIG. 1 is a front view of a new design of an information handling device with graphical user interface; and, FIG. 2 is a front view of the user interface illustrating placement of graphical elements within a second embodiment thereof.

In FIGS. 1-2, the outer rectangle shown by broken lines is the edge of an information handling device screen shown for the purpose of illustrating environmental structure and forms no part of the claimed design.

1 Claim, 2 Drawing Sheets

FIG. 1

FIG. 2
